UNITED STATES PATENT OFFICE.

JOHN E. HUME, OF CLINTON, MASSACHUSETTS, ASSIGNOR TO CROMPTON & KNOWLES LOOM WORKS, OF WORCESTER, MASSACHUSETTS, A CORPORATION OF MASSACHUSETTS.

WEFT DETECTOR ON LOOM TRANSFERRER ARM.

Application filed December 29, 1925. Serial No. 78,181.

This invention relates to weft detectors for looms and more particularly to the type of detector mounted on a regularly reciprocating transerrer arm such as set forth in Patent No. 1,551,219.

Detectors of this type usually employ a transerrer arm having a plunger slidably mounted therein normally locked in nonindicating position and moved up and down with the transerrer arm without cooperating with an indicating lever pivoted to the replenishing mechanism. There is also mounted on the transerrer arm a lever having pivoted at one end thereof a detector of the side slip type which is moved into engagement with the surface to be detected on each downward stroke of the transerrer arm. It is found that the detector is subject to undesirable movements resulting occasionally in false indications which unlock the plunger so that the latter gives an improper indication. It is the general object of my present invention to improve upon the control for the plunger to the end that non-indicating movements of the detector shall not release the plunger.

It is a further object of my invention to provide the transerrer arm with a locking latch having a surface adjacent the detector to limit movement of the latter in an indicating direction until the yarn of the bobbin has been reduced to a point where indicating movements of the detector may properly occur.

It is a further object of the invention to provide a transerrer arm carried detector held against indicating movement until exhaustion approaches by a plunger lock under which the detector moves at exhaustion so that continued downward movement of the transerrer serves positively to unlock the plunger.

With these and other objects in view which will appear as the description proceeds, my invention resides in the combination and arrangement of parts hereinafter described and set forth in the claims.

In the accompanying drawings wherein I have shown a convenient embodiment of my invention,

Fig. 1 is a vertical section through a loom transerrer arm having my invention applied thereto, the section being taken parallel to the axis of the shuttle and showing the de-

tector in its extreme down position and co- 55 operating with a full bobbin,

Fig. 2 is a view similar to Fig. 1 but showing the detector in engagement with a bobbin having a nearly depleted supply of weft,

Fig. 3 is a view similar to Fig. 2 but 60 showing the parts in indicating position, and

Fig. 4 is a vertical section on line 4—4 of Fig. 2.

Referring to the drawings it will be seen that I have provided a transerrer arm 10 65 extending parallel to and over the shuttle and having pivotally mounted as at 11 an indicating lever 12 the inner or right hand end of which as viewed in the drawings is provided with a lug 13 which cooperates 70 with a yielding stop S of the type set forth in the aforesaid patent. The left or outer end of said lever has pivoted thereto as at 14 a detector 15 having an upwardly extending portion to receive a stop screw 16 to cooperate with a portion of the lever and limit outward movement of the detector tip 17. Said tip, which is preferably roughened and proportioned to engage the bobbin, normally 75 lies to one side of a vertical line passing 80 through pivot 14. Slidably mounted on said arm 10 is an indicating plunger 18 around a portion of which lies a compression spring 19 the function of which is to move said detector from the position shown in Fig. 1 to 85 the position shown in Fig. 3 at indication of weft exhaustion so that as the transerrer arm is raised movement will be conveyed to a lever (not shown). The matter thus far described is substantially the same as that 90 set forth in the aforesaid patent.

In carrying out my invention I provide the outer end of plunger 18 with a notch 30 and pivot on said transerrer arm as at 31 a lock latch 32 having on the upper portion 95 thereof a detent 33 for notch 30 and an extension 34 held against a portion of the arm 10 by a leaf spring 35 secured as by screw 36 to the arm 10. Said leaf spring tends 100 normally to hold the latch in the position indicated in Fig. 1. The lower end of said latch 32 has a curved face 37 concentric with the center 11 and also has a horizontally extending arm 38 to be engaged and raised by the detector.

Under normal operations when sufficient yarn for continued weaving is present the transerrer arm 10 is moved downwardly on

alternate or detecting beats of the loom so that a transferrer shoe 20 will closely approximate the butt of the bobbin B. On its descent lug 13 will engage yielding stop S as contemplated in the aforesaid patent and will serve to move the detector tip 17 against the bobbin. So long as sufficient yarn is present to prevent sliding movement of the detector along the bobbin the yielding stop 10 will be depressed and the detector will be held against lateral movement.

As exhaustion approaches the parts will be as shown in Fig. 2, the detector tip 17 moving to a lower position than indicated in 15 Fig. 1 but still being held against sidewise movement by engagement with the face 37. As weaving continues a time will come when there is insufficient yarn to prevent the detector from sliding and as the transferrer 20 descends the tip 17 will move to the right under arm 38 and as the transferrer arm continues downwardly further descent of the latch 32 is prevented by the tip and bobbin thereunder and latch 32 is moved to the position 25 shown in Fig. 3 against the action of leaf spring 35. The effect of this movement is to release the plunger 18 and the same moves to the indicating position shown in Fig. 3. Upon the rising movement of the transferrer arm indicaton will be given as contemplated in Patent No. 1,372,316.

Spring 35 is made sufficiently strong to prevent improper movement of the latch 32 should the same be struck a lateral blow by 35 detector tip 17 and the detector can move to the unlocking position as shown in Fig. 3 only at such times as the detector tip lies under the arm 38. In this way the positive downward motion of the transferrer arm 40 is relied upon to unseat the latch.

From the foregoing it will be seen that I have provided a weft detector for the transferrer wherein the plunger is held locked by a latch which is unaffected by 45 improper movement of the detector tip 17 and that releasing of the plunger by the latch depends upon the interposition of a portion of the detector between the bobbin and the arm 38 of the latch so that the last part of 50 the downward motion of the transferrer arm on the indicating beat will positively unseat the latch 32. It will further be seen that inasmuch as surface 37 is substantially 55 concentric with the axis of the lever 12 said surface will be equally effective in all vertical positions of the detector to restrain excess movement thereof.

Having thus described my invention it will be apparent that changes and modifications may be made therein by those skilled 60 in the art without departing from the spirit and scope of the invention, and I do not wish to be limited to the details herein disclosed but what I claim is:

1. In a weft replenishing loom having a

transferrer arm regularly reciprocated toward and from the weft supply to be detected and having a plunger slidably mounted therein, a latch to hold the plunger normally in locked position, and a detector supported by the transferrer arm and movable along a depleted bobbin so that a portion of said detector will lie under the latch upon moving at substantial exhaustion before the transferrer finishes its movement toward the 75 supply to be detected, whereby continued movement of the transferrer arm toward the weft supply will move the latch to a position to unlock the plunger.

2. In a weft replenishing loom having a 80 transferrer arm regularly reciprocated toward and from the weft supply to be detected and having a plunger slidably mounted therein, a weft detector mounted for pivotal motion with respect to the transferrer 85 arm, a latch mounted on the transferrer arm and normally locking the plunger in non-indicating position, and an arm formed on said latch, said detector moving at substantial exhaustion so that a portion thereof lies 90 under the arm before the transferrer finishes its movement toward the supply to be detected, whereby continued movement of the transferrer arm after said portion of the detector lies under the arm will move 95 said latch to unlocking position.

3. In a weft replenishing loom having a 100 transferrer arm regularly reciprocated toward and from the weft supply to be detected and having a plunger slidably mounted therein, a lever pivotally mounted on the transferrer arm, a detector member mounted for free limited movement on the lever, and a latch to lock the plunger in non-indicating 105 position and having a surface substantially concentric with respect to the axis of the lever and equally effective in all positions of the detector to restrain excess movement of the latter, said latch being moved to unlock the plunger at substantial 110 exhaustion of weft.

4. In a weft replenishing loom having a 115 transferrer arm regularly reciprocated toward and from the weft supply to be detected and having a plunger slidably mounted therein, a lever pivotally mounted on the transferrer arm, a detector mounted for free limited movement on the lever, a latch pivotally mounted on the transferrer arm and having a portion to lock the plunger in 120 non-indicating position, and resilient means mounted on the transferrer arm to hold said latch in locking engagement with the plunger, said detector having a portion to move under the latch at the time of indication of weft exhaustion to move the latch 125 against the resilient means and unlock the plunger as the transferrer arm completes its movement toward the weft supply.

5. In a weft replenishing loom having a 130

transferrer arm regularly reciprocated toward and from the weft supply to be detected and having a plunger slidably mounted therein, a lever pivotally mounted on the 5 transferrer arm, a detector mounted on said lever for free limited movement, a latch having a portion to engage and be stopped by a part of the transferrer arm, resilient means to hold said portion against said part, 10 and a hook formed on the latch normally located in a notch formed on the plunger, said detector moving longitudinally along a substantially denuded bobbin into engagement with a portion of the latch to move 15 the latch to unlocking position.

6. In a weft detecting mechanism, a regu-

larly reciprocating transferrer arm having a plunger slidably mounted therein, a detector supported by the transferrer arm and movable along a substantially denuded bobbin at the time of weft exhaustion, and a latch normally holding the plunger in non-indicating position said detector at the time of substantial exhaustion of weft moving under and having direct engagement with 20 the latch to move the latter to unlocking position at the time of indication of weft exhaustion.

In testimony whereof I have hereunto affixed my signature.

JOHN E. HUME.
